UNITED STATES PATENT OFFICE.

WILLIAM H. H. HUNTER, OF CINCINNATI, OHIO.

DENTAL PLUGGER.

SPECIFICATION forming part of Letters Patent No. 268,900, dated December 12, 1882.

Application filed April 26, 1882. (Model.)

To all whom it may concern:

Be it known that I, WILLIAM H. H. HUNTER, of Cincinnati, in the county of Hamilton and State of Ohio, have invented certain new and useful Improvements in Dental Pluggers, of which the following is a specification.

My invention is in the nature of an improvement in that class of dental pluggers which are automatic in the operation of the mallet or hammer—that is, by pressing the point or tool against a resistance—as the foil in a tooth-cavity—and pushing the barrel or case of the instrument toward the point the mallet is released from its detent to give the desired blow. 15 When the downward pressure on the barrel is relaxed the barrel and mallet are lifted back to their normal positions by an auxiliary spring and the mallet caught by an appropriate detent, in readiness for a second blow, and so on as 20 rapidly as the barrel or case of the instrument can be pushed toward the point of the tool and relaxed. The blows of the mallet are repeated automatically. The force which drives the mallet down onto the tool is a spring which is 25 compressed or extended as the barrel is pushed down.

The objects of my invention are to provide a novel combination of devices for raising and releasing the mallet, to enable a long and heavy 30 mallet to be employed, and to vary the force of the blow given by the mallet. These objects I accomplish by the mechanism illustrated in the accompanying drawings, in which—

Figure 1 is a longitudinal section on the line 35 xx of Fig. 4, showing the mallet down. Fig. 2 is a longitudinal section on the line yy of Fig. 4, showing the mallet up. Fig. 3 is an enlarged plan of the head of the case. Fig. 4 is an enlarged transverse section on the line 40 zz of Fig. 1, and Fig. 5 is an enlarged transverse section on the line ss of Fig. 1.

Similar letters of reference indicate similar parts.

A is a barrel or case of cylindrical form, and 45 of such diameter and length as will make it convenient to handle in the ordinary operation of filling cavities in teeth.

B is a tool or tool-holder, as may be preferred. If a tool-holder is desired, it is provided with a screw-socket at b , into which plug-

ging tools of different sizes and forms may be screwed. If a tool, as shown in Figs. 1 and 2, is preferred, it is made solid from end to end, and each tool must be provided with the head or shank b' to pass freely within the nozzle a 55 of the barrel or case of the instrument. The tool holder or head b of each tool—of which there may be any desired number—is provided with a slot, b^2 , made parallel with the axis thereof, and having a length somewhat in excess of the combined length of movement of the mallet and diameter of the catch-pin.

C is the spring-catch, consisting of the curved spring c , closely fitting the nozzle a , when down, and a pin, c' , which passes through the 65 hole a^5 in the nozzle and engages with the slot b^2 of the tool B . The diameter of the pin c' and width of the slot b^2 are such that the former plays freely within the latter. By reason of the shoulders or stops formed by the 70 ends of the slot the motion of the pin c' is limited by the slot b^2 . The end of the spring c is slightly raised above the surface of the nozzle a to enable the operator to lift the spring and pin c' with his thumb-nail to release the 75 tool, whereby one tool can be quickly substituted for another.

D is the mallet, drilled centrally from end to end to embrace the piston or stem E , which plays freely therein and rests upon the head 80 of the tool B , as shown in Figs. 1 and 2.

e is a hook or catch upon the stem E , which engages with the hook or catch d of the mallet and retains it suspended, as it were, against the force of the springs F until released by 85 means of the bevel e' on the stem E impinging against the beveled guide-piece g , adjustably secured to the head or cap G by means of the screw g' and slot g^2 . (Shown in Figs. 2 and 3.) The stem E being forced laterally from its 90 normal position by the guide-piece g far enough to disengage the hooks or catches d and e , the mallet D is then forcibly driven down on the head of the tool B by the springs F . The stem E terminates at its upper end in arm e^2 , 95 (or this arm may be an independent piece and secured by any proper means to the stem,) to which an elastic rubber band or spring H is attached to raise the barrel or case A of the plugger when the pressure in a downward di- 100

irection is relaxed. The lower end of the spring H is rove around the pin or stud a in the side of the barrel or case A.

5 a^2 is an annular flange formed in the case or barrel, at the lower end thereof, above which the head of the tool B projects slightly when the barrel A is pushed down as far as the slot b^2 and pin c' permit, whereby the full force of the blow of the mallet D is received by the tool.

10 $d' d'$ are a pair of arms rigidly secured to and moving up and down with the mallet D in guide-slots $a^3 a^3$, cut in the barrel A. The lower ends of the arms are provided with shoulders $d^2 d^2$, which, when the barrel or case A is raised 15 by the spring H, rest upon the bottoms of the slots $a^3 a^3$ and raise the mallet to effect the engagement of the hooks or catches d and e . The length of the guide-slots $a^3 a^3$ is such that when the mallet D has fallen upon the head 20 of the tool B there is a slight clearance under the shoulders $d^2 d^2$, in order that the tool shall receive the full force of the blow. The upper ends of the arms $d' d'$ are provided with forks $d^3 d^3$, in which the springs F F are rove, as 25 also around the fixed studs or pins $a^4 a^4$ on the barrel. The springs F are of rubber or other suitable material, of which any convenient strength or number may be used.

By reference to Figs. 1 and 2 it will be observed that the mallet D is turned down smaller 30 than the diameter of the barrel, excepting at the ends, the diameters at the ends being sufficiently smaller than the bore of the barrel to enable the mallet to slide freely therein.

35 The action of the plugger, as already imperfectly outlined, is as follows: The case or barrel A being in the elevated position, the hooks d and e engaged, and the point of the tool B resting against a resistance—as the foil 40 in the cavity of a tooth—the barrel is grasped by the operator and pushed downward until the catches or hooks d and e are disengaged by the swell e' on the stem E coming in contact with the guide-piece g, (which may be adjusted to effect an earlier or later release of

the mallet, as desired,) when the mallet D is driven downward by the force of the springs F F acting through the arms $d' d'$. The blow of the mallet, falling with its full force upon the head of the tool B, condenses the foil in 50 the tooth-cavity. Directly the mallet has fallen the pressure on the barrel in a downward direction is relaxed, when the case A and mallet D are lifted to their normal position by the spring H. The stem or piston E 55 rests upon the head of the tool B, and has no other motion than that imparted to it in a lateral direction by the guide-piece g. The return of the case and mallet to their normal positions is accompanied by a re-engagement 60 of the hooks or catches d and e , when a second blow of the mallet is given by again pressing the barrel A downward toward the point, and so on for as many blows as may be desired.

I am aware that automatic dental pluggers 65 in which the tool is operated upon by a reciprocating mallet driven by a spring within a case or barrel, the mallet being raised and released by the rise and fall of the case, are not new, and this I do not claim. 70

Having described my invention, what I claim is—

1. The combination of a barrel or case, A, mallet D, stem E, hooks d and e , adjustable guide g, and springs F F, arranged for operation substantially as described. 75

2. The combination of the stem E, swell e' , guide g, provided with a slot, g' , and binding-screw g^2 , and the cap G, substantially as and for the purpose described. 80

3. The combination of the barrel A, stud a' , spring H, arm e^2 , stem E, and tool B, substantially as and for the purpose described.

In testimony whereof I have signed my name to the foregoing specification in the presence 85 of two subscribing witnesses.

WILLIAM H. H. HUNTER.
